UNITED STATES PATENT OFFICE.

WILBUR R. KIMBALL, OF NEW YORK, N. Y., ASSIGNOR TO CHRISTOPHER W. YOUNGMAN, OF NEW YORK, N. Y.

MOUTHPIECE FOR SPEAKING-TUBES OR TELEPHONES.

SPECIFICATION forming part of Letters Patent No. 783,440, dated February 28, 1905.

Application filed October 17, 1903. Serial No. 177,438.

To all whom it may concern:

Be it known that I, WILBUR R. KIMBALL, a citizen of the United States, and a resident of the borough of Manhattan, city, county, and State of New York, have invented certain new and useful Improvements in Mouthpieces for Speaking-Tubes or Telephones, of which the following is a specification accompanied by drawings.

10 This invention relates to mouthpieces for speaking-tubes and telephones; and its objects are to prevent the sound of the voice from being heard by those near the speaker and confine the voice so that secrecy may be obtained 15 in the transmission of messages.

Another object of the invention is to improve upon the construction and efficiency of mouthpieces for carrying out these objects and at the same time increase the volume of 20 sound and distinctness conveyed through the mouthpiece.

Further objects of the invention will hereinafter appear; and to these ends the invention consists of a device for carrying out the 25 above objects embodying the features of construction, combinations of elements, and arrangement of parts having the general mode of operation substantially as hereinafter fully described and claimed in this specification and 30 shown in the accompanying drawings, in which—

Figure 1 is a longitudinal sectional side view of a mouthpiece embodying the invention, and Fig. 2 is a sectional view of the same on the 35 line $\times \times$ of Fig. 1. Fig. 3 is an end view of the detachable mouthpiece.

Referring to the drawings, A represents a casing of any suitable rigid material, which may be metal, hard rubber, or any other desired material. The outer casing A, of any suitable shape, as shown, is further reinforced by an interior lining of sound-deadening material B, which may be rubber, fibrous material, or any material which is a poor conductor 40 of sound. The lining B, as shown, is extended around a portion of the end C of the casing A, as shown at D, up to the central tube E, of any suitable shape, which may be

of any suitable material—as, for instance, paper, lightness and strength being desired. 50

Outside of the central tube E are arranged the tubes F, of suitable light material, such as used for tubes and which are preferably open at both ends. I have shown the tubes F separated from each other and assembled in the 55 space around the central tube E by way of illustration only, for it is obvious that different constructions may be used—as, for instance, the tubes may be of different cross-sections, either square or round, or of other form and 60 size, and they may be formed in one or more blocks of material, it being only essential that a nest of tubes surround the central tube E.

The object of the tubes F is to break up sound-waves which otherwise interfere by reflection 65 against the sides of a closed chamber, and thereby prevent reverberations and to a large extent eliminate the resonance of the chamber. By this construction clearness and distinctness are obtained. 70

It is not necessary that the tube E extend for the entire length of the tubes F. I have shown it so extending in this instance by way of illustration only. As shown, the tube E extends beyond the end of the casing A, as at 75 F', and is provided with a nipple G at one side, communicating with the interior of the tube. In this instance a rubber tube H is secured to the nipple, the object being to provide a tube of any suitable character or material 80 communicating with the interior of the tube E, in contradistinction to a mere aperture in the side of a tube, and I am not to be understood as limiting myself to the exact construction shown and described, because other constructions will be found equally efficient. The apparatus so far described is adapted to be attached to the mouthpiece of an ordinary telephone, and, as shown, I represents the usual mouthpiece, and upon the casing A are 85 arranged the spring-clips J, adapted to spring over the mouthpiece I and maintain the device in position, although other forms of fasteners or screw connection will be found equally efficient. Preferably within the clips 90 J is a flexible bulb K, forming a pneumatic 95

seal around the end of the tube E, which is tightly pressed against the mouthpiece I when the device is clamped in position.

The object of the tube H communicating with the tube E is primarily to lead off the compressed air and surplus air-currents without interfering with the transmission of the sound-waves, and it has been found that by providing a tube H of appreciable length, as described, the escaping sound-waves are attenuated to such an extent that they become practically inaudible at a few inches distance. It will also be seen that according to this construction the air impulses are led off in a direction transverse to the direction of travel of the sound-vibrations, and this without interference with said sound-vibrations, which are transmitted more clearly and distinctly to the diaphragm than heretofore.

At the transmitting end of the device a suitable flexible, elastic, or pliable mouthpiece O may be provided, which, as shown, fits about or within the end of the casing A and is preferably provided with a grating of porous material P to prevent interference with the tubes inside of the casing.

If desired, a pneumatic edge may be provided for the mouthpiece in any suitable manner—as, for instance, by suitably securing a flexible pneumatic tube O' upon the edge of the mouthpiece. By this means the elastic pressure of the pneumatic edge against the face of the speaker prevents the escape of sound-waves.

Obviously some features of this invention may be used without others, and the invention may be embodied in widely-varying forms.

Therefore without limiting the invention to the apparatus shown and described nor enumerating equivalents, I claim, and desire to obtain by Letters Patent, the following:

1. A mouthpiece for speaking-tubes and telephones, comprising a casing forming a substantially closed chamber when in use, and a plurality of tubular passages within the casing for breaking up the sound-waves, thereby reducing the resonance of the chamber, for substantially the purposes set forth.

2. A mouthpiece for speaking-tubes and telephones, comprising a casing forming a chamber adapted to be arranged in substantial axial alinement with the mouthpiece of the telephone and close or fill the opening thereof, and a tube or passage-way arranged transversely to the axis of the chamber and communicating with the chamber at the forward end nearest the telephone, for conducting excess of air-pressure from the chamber and at the same time rendering the sound-waves leaving said tube or passage-way substantially inaudible, for substantially the purposes set forth.

3. A mouthpiece for speaking-tubes and telephones, comprising a casing forming a chamber having a passage-way therethrough, a plu-

rality of additional tubular passages within the casing for breaking up the sound-waves thereby reducing the resonance of the chamber, and means for separating the air-currents from the sound-waves, for substantially the purposes set forth.

4. A mouthpiece for speaking-tubes and telephones, comprising a casing, a plurality of passages within the casing for reducing the resonance thereof, and means for separating the air-currents from the sound-waves, for substantially the purposes set forth.

5. A mouthpiece for a telephone or speaking-tube and for analogous uses, having a main body portion composed of stiff material 80 having a suitable elastic, plastic, flexible or pliable lining with a pneumatic edge connected to said lining, thereby enabling the inner surfaces of the mouthpiece to follow and conform to the facial movements while speaking, 85 thus preventing the escape of sound-waves, for substantially the purposes set forth.

6. A mouthpiece for speaking-tubes and telephones, designed to muffle the voice of the speaker, said device consisting of a stiff casing 90 having an interior lining of sound-deadening material, and provision for venting the mouthpiece to atmospheric air, whereby the air-currents are separated from the sound-waves, and the voice muffled, for substantially the purposes set forth.

7. A mouthpiece for speaking-tubes and telephones, comprising a casing having a lining of sound-deadening material, and a tube or passage-way communicating with the interior 100 of said casing and extending therefrom beyond the exterior of the casing, for separating the air-currents from the sound-waves, for substantially the purposes set forth.

8. A mouthpiece for speaking-tubes and telephones, comprising a casing forming a chamber adapted to be arranged in substantial axial alinement with the mouthpiece of the speaking-tube or telephone, and cover or fill the opening thereof, and a tube or passage-way 110 communicating with the interior of said chamber at the forward end of the chamber nearest the telephone, and extending therefrom beyond the exterior of the casing, for conducting the excess of air-pressure from the chamber and at the same time render the sound-waves leaving said tube or passage-way substantially inaudible, for substantially the purposes set forth.

9. A mouthpiece for speaking-tubes and telephones, comprising a casing open at both ends and adapted to be arranged in front of the speaking-tube or telephone in axial alinement therewith, with one end covering or closing said speaking-tube or telephone, and a tube or passage-way communicating with the interior of said casing at the forward end of the casing nearest the telephone and extending therefrom beyond the exterior of the casing, for conducting the excess of air-pressure 130

from the chamber and at the same time render the sound-waves leaving said tube or passageway substantially inaudible, for substantially the purposes set forth.

- 5 10. A mouthpiece for speaking-tubes and telephones, designed to muffle the voice of the speaker, said device consisting of a stiff casing having an interior lining of sound-deadening material, provision within the casing for 10 breaking up the sound-waves, thereby reducing the resonance of the chamber, and provision for venting the mouthpiece to atmos-

pheric air, whereby the air-currents are separated from the sound-waves and the voice muffled, for substantially the purposes set 15 forth.

In testimony whereof I have signed this specification in the presence of two subscribing witnesses.

WILBUR R. KIMBALL.
